UNITED STATES PATENT OFFICE.

LOUIS SANDERS, OF NEW YORK, N. Y.

DESIGN FOR A BODY PORTION FOR BELTS.

SPECIFICATION forming part of Design No. 32,350, dated March 18, 1900.

Application filed January 29, 1900. Serial No. 3,238. Term of patent 3½ years.

To all whom it may concern:

Be it known that I, LOUIS SANDERS, a citizen of the United States, and a resident of the city of New York, borough of Brooklyn, in the county of Kings and State of New York, have invented and produced a new and original Design for the Body Portion of a Belt, of which the following is a specification, reference being had to the accompanying drawings, forming a part thereof, in which—

Figure 1 is a rear elevation of the body portion of a belt embodying the features of my design; and Fig. 2 is a transverse section through the body portion of the belt, the section being taken on the line 2 2 of Fig. 1.

The design consists in the marginal contour of the body portion A of a belt and the outer surface ornamentation B, in which the longitudinal marginal lines of the body section are oppositely curved at the central portion

of the body and are continued to the ends of the said section by converging lines more or less straight. The surface ornamentation B appears embossed on the outer face of the body A and represents longitudinal cord 25 structures which extend from end to end of the body.

Having thus described my invention, I claim as new and desire to secure by Letters Patent—

The design for the body portion of a belt herein shown and described.

In testimony whereof I have signed my name to this specification in the presence of two subscribing witnesses.

LOUIS SANDERS.

Witnesses:

J. FRED. ACKER,
JNO. M. RITTER.
